DINING FORK OR SIMILAR ARTICLE

Oliver Messel, London, England (% Imperial Knife
Associated Companies, Inc., 1776 Broadway, New York 19, N.Y.)

Filed June 1, 1964, Ser. No. 80,209

Term of patent 14 years

(Cl. D54—12)

FIG. 1 is a top plan view of a dining fork showing my new design;

FIGS. 2 and 3 are, respectively, side elevational and bottom plan views thereof; and

FIG. 4 is an enlarged sectional view taken along the line 4—4 of FIG. 1.

The dominant feature of my design resides in the sharply upturned handle tip in combination with a series of three overlapping shallow steps on the back surface of the handle where the same joins the common base of the tines, all as shown.

I claim:

The ornamental design for a dining fork or similar article, as shown and described.
